**METHOD AND APPARATUS FOR INCREASING OUTPUT
OF CAR ENGINE AND PURIFYING EXHAUST GAS**

DETAILED DESCRIPTION OF THE INVENTION

This invention relates to a method and apparatus for increasing the output of an internal combustion engine, particularly for vehicles, and the primary object of the invention is to expedite the mixing of volatile oil and air so as to enhance combustion efficiency and to achieve maximum purification of exhaust gas, irrespective of the composition of fuel fed.

In the accompanying drawings,

FIG. 1 is a schematic illustration explaining the principles of the method of the present invention,

FIG. 2 is an illustration showing an embodiment of the apparatus used for practicing the method of the present invention, and

FIG. 3 is a longitudinal sectional view showing an embodiment of the valve mechanism used in the above-said apparatus.

The fuel oil for vehicles, which is generally sold on the market, is classified into two types. One for use in summer season and the other for use in winter season. These types differ from each other in the mixing proportion of the constituents and are selected for use according to the conditions under which the oil is used. In winter season, the proportion of such components that are of low boiling point is increased so as to facilitate starting and acceleration of the engine even under a low temperature condition. In summer season, on the other hand, there is usually used the oil in which the proportion of the low boiling point components is decreased in order to preclude spontaneous vaporization or volatilization which may take place under hot temperature. Although the total calorific powers produced by these two types of oil under the state of perfect combustion are substantially equal to each other, the rate of volatilization as well as the rate of vaporization in the cylinder are varied according to the proportion of the components in the fuel composition, and this results in varying the rate of combustion in the engine, with resultant change of engine efficiency, thus greatly affecting the general output of the engine. Also, the volatile oil atomized in the carburettor must be further expanded in the intake pipe and in the cylinder as well and must be perfectly mixed up with air by the time it is ignited. If this air and oil mixing is improper, no perfect combustion can be obtained.

It is known that a low boiling point material having good volatility and vaporizability is preferred for making a perfect mixture, but the volatile oil abundant with such low boiling point components is subject to quick vaporization or dissipation under the effect of natural conditions such as atmospheric temperature or pressure. Also, the total amount of produced hydrocarbon per unit capacity of the internal combustion engine is limited, with resultant poor combustion rate and reduced engine output.

On the other hand, a volatile oil (gasoline) having abundant high boiling point components tends to produce many residues of non-evaporated fraction during combustion, so that it is hardly possible to obtain a perfect air-gas mixture, resulting in imperfect combustion with resultant excess reduction of the combustion rate.

The present invention is designed to eliminate all of these defects by providing improved means for expediting perfect mixture of volatile oil and air irrespective of the component proportion of the fuel composition and for achieving maximum purification of exhaust gas. The essentials of the invention reside in the facts that in the fuel system of an internal combustion engine consisting of an air cleaner 1, a carburettor 2 and a manifold 3, there is provided a secondary air supply pipe 4 halfway between said carburettor 2 and manifold 3 to thereby introduce into the fuel system a suitable amount of secondary air, and that a weak radioactive material 6 (for example a natural radioactive ore) is provided at the inlet 4' of said air pipe 4 so as to apply weak radiation to the air 5 taken in through said pipe. The natural radioactive ore used (which

may be of an α -ray, β -ray or γ -ray type) is preferably of the uranium series, radium series or trium series.

Also in FIG. 1, reference number 7 designates an engine for vehicles and 8 a throttle valve.

- 5 There is known in the art a method in which a certain suitable amount of air (for example, about 10 percent of the entire amount of air fed) is introduced substantially halfway between the carburettor 2 and the manifold 3 to thereby enhance mixing efficiency of fuel oil and air. However, achievement of this mixing depends on a physical turbulent flow and is therefore likely to be affected by natural conditions more or less depending on the composition of fuel oil, so that it is impossible to overcome fully the above mentioned defects. It is also known that if the mixture is exposed to weak radiation, the high boiling point components of the volatile oil, upon receiving radioactivity, are decomposed, with a part thereof being converted into a medium boiling point component and with the remaining active molecules being combined with the low boiling point components to turn also into a medium boiling point component or an isomeric substance which is easily reduced into liquid or atomized state, thus eliminating the necessity in selecting fuel oil of the composition best suited for the natural conditions under which it is used.
- 10 25 With these facts in view, the present invention has realized means for obtaining the best mixture of volatile oil and air and for changing the amount and rate of vaporization of the volatile oil components into the optimum ones, thereby to achieve maximum enhancement of combustion efficiency.
- 15 30 The invention will be described in more detail hereinafter by way of its preferred embodiment with reference to the accompanying drawings.

- 20 Referring first to FIG. 1, there is shown a schematic illustration explaining the general principles of the method of the present invention. As will be noted, the invention utilizes a conventional type fuel system in which the air introduced through an air cleaner 1 is mixed up with fuel in a carburettor 2 and then flows into a manifold assembly 3, and is characterized by a secondary air supply pipe 4 disposed in front of said manifold assembly 3, said secondary air pipe 4 being adapted to admit a suitable predetermined amount of secondary air 5 which has been subjected to weak radiation. It is to be noted here that the air, which has been subjected to said radiation (α -rays or β -rays), is ionized and furnished with same electric charges which serve to animate the isolating action between the molecules, thus facilitating their combination with fuel molecules when they are joined with the mixture gas under agitation, thereby attaining appreciable enhancement of mixing efficiency.

- 25 40 45 50 55 Also, since the secondary air 5 still has a residue of radiation at the moment when it is joined with the mixture gas, it is possible to convert the volatile oil components into a desired boiling point condition by the action of the residual weak radiation, thereby achieving additional enhancement of combustion efficiency.

- 60 The above process will be described in a more detailed manner below. It is known that if the air fuel ratio of the mixture fed into the carburettor is lower than what is normally required by the engine, working performance of the vehicle is reduced and also fuel consumption is enlarged. It was found, however, that introduction of secondary air, which has been ionized with application of weak radiation, proves helpful to realize normal operation at a minimum air fuel ratio without impeding working performance of the vehicle. This is considered to be attributable to the following reasons:

- 65 70 75 1. The air fuel ratio required for best combustion is solely related to the carbon/hydrogen ratio in hydrocarbon, and has no relation to the molecular structure.
2. The ignition phenomenon takes place in the following manner: heat energy fed into the cylinder acts on hydrocarbons to decompose some of them into several radicals having ionization potentials, and these radicals, in turn, act on the remainder of hydrocarbons to cause their decomposition in a successive manner, with the result that the number of the radi-

screen and carrying the pulverized radioactive material.

2. The combination of claim 1 and wherein said filter paper is removable from said screen.

3. The combination of claim 1 and wherein said pulverized material is a natural radioactive ore of the uranium series, the radium series, or the trium series.

4. The combination of claim 1 and wherein a valve means is carried by said supply means and has a normally closed position closing said supply means, said valve means responding

automatically to a drop in pressure in the intake manifold for opening said supply means to admit secondary air.

5. The combination of claim 1 and wherein said supply means is in the form of a pipe having an inlet for secondary air, and said means for exposing the secondary air to the radioactive material being situated at said inlet.
